UNITED STATES PATENT OFFICE.

HARRY T. LOOMIS, OF BROOKLYN, NEW YORK.

BURIAL-GARMENT AND METHOD OF MAKING THE SAME.

1,336,248.

Specification of Letters Patent.

Patented Apr. 6, 1920.

Application filed March 20, 1919. Serial No. 283,735.

To all whom it may concern:

Be it known that I, HARRY T. LOOMIS, a citizen of the United States, and residing at Brooklyn, in the county of Kings and State 5 of New York, have invented certain new and useful Improvements in Burial-Garments and Methods of Making the Same, of which the following is a specification, such as will enable those skilled in the art to 10 which it appertains to make and use the same.

This invention relates to garments and particularly to burial garments and especially coats, and the object of the invention 15 is to provide a garment of this class with lapels and a collar without binding, stitching or other needlework whereby the manufacture of the garment is simplified and made more economical and a better garment 20 produced; and with this and other objects in view the invention consists in a garment of the class specified, formed as herein described and in the method of making said garment herein set out.

25 The invention is fully disclosed in the following specification, of which the accompanying drawings form a part, in which the separate parts of my improvement are designated by suitable reference characters in 30 each of the views, and in which:—

Figure 1 is a plan view of a garment involving my invention and placed in a display box;

Fig. 2 a detail view of part of the garment 35 before it is completed with part of the construction broken away;

Fig. 3 a section on the line 3—3 of Fig. 2;

Fig. 4 a section similar to Fig. 3 but showing a modification;

40 Fig. 5 a diagrammatic plan view of a part of the apparatus employed in making my improved garment and partially showing the method of its operation;

Fig. 6 a partial section on the line 6—6 of 45 Fig. 5;

Fig. 7 a diagrammatic plan view showing patterns cut from blanks formed by the apparatus shown in Fig. 5;

Fig. 8 a diagrammatic side view of the 50 apparatus shown in Fig. 5;

Fig. 9 a side diagrammatic view indicating the dies and the method of cutting the patterns shown in Fig. 7;

Fig. 10 a view similar to Fig. 7 but showing only a part of one pattern on an en-

larged scale, and indicating the last step in the process of making said patterns;

Fig. 11 a view similar to Fig. 5 but showing only a part of the construction and showing a modification;

Fig. 11^a a view similar to Fig. 7 but showing the patterns cut from the blanks formed by the apparatus shown in Fig. 11; and,

Fig. 12 a view similar to Figs. 5 and 11 but showing another modification in the apparatus and the method of its operation.

In Fig. 1 of the accompanying drawing I have shown at 15 an ordinary display box and at 16 a burial garment or coat made according to my invention, and as will hereinafter appear, my invention consists in the method of making or forming the lapels 17 of the coat and the collar 18 without edge stitching of any kind, and at the same time so forming said lapels and collar that they 70 will retain their position as shown in the drawing and present a highly finished appearance similar to, or superior to, that obtained when said lapels and collar are stitched.

In Figs. 2 and 3 of the drawing, I have indicated at 19 one-half of the coat portion of the garment 16 shown in Fig. 1, and one of the lapels 17 and a part of the collar 18 and, in this form of construction, the collar 85 and lapel are made up of a part 19 and a front strip 20 composed of the same material as the part 19, and between which is placed a lining strip 21. The strips 20 and 21 are secured to the part 19 by inner and 90 outer strips of gutta percha or similar material 22 and 23, and between the lapels 17 and the collar 18 are formed the usual V-shaped cut-outs 24, and in completing these parts of the coat of the garment, as 95 shown at 19 in Fig. 2, a line of stitching or imitation stitching 25 is formed between the lapel and collar portions and extending from the inner end of the V-shaped cut-out portion 24 upwardly and inwardly as indicated in Fig. 2 to give the lapel and collar portions of the coat the proper appearance, or the appearance of a collar made independent of the lapels and stitched thereto.

In Fig. 4 of the drawing, I have shown a 105 slight modification in which the lining strip 21 is omitted and the strip 20 is secured to the part 19 by a single strip of gutta percha 22^a but in both of the forms of construction shown in Figs. 2 to 4 inclusive, the strips 20 110

and 21 are so secured to the part 19 by the 5 gutta percha strips 22-24 as to form on the inner edges of the strips 20 and 21 attaching flaps 26, which extend the full length of the part 19 and to which the vest or vest portion 27 of the garment is attached by stitching or otherwise in the usual manner in the manufacture of garments of this class.

The foregoing clearly sets out the construction of one-half of the garment, or the lapel and collar thereof, and in Figs. 5 to 10 inclusive, I have diagrammatically illustrated the apparatus and the method by which the separate parts of the garment are made, or the various steps in the method of making such garment, or the lapel and collar portions thereof.

In Fig. 8 of the drawing, I have indicated at 29 a spool or roll of fabric 30 from 20 which the main body portion of the separate parts 19 of the garment are made, and at 31 I have shown a spool or roll of the strip 20 employed as shown in Figs. 2 and 3 of the drawing, and at 32 a spool or roll of the lining strip 21 employed in Figs. 2 and 3, and at 33 and 34 I have shown spools or rolls of the gutta percha strips 22 and 23. In practice, the sheet 30 together with the strips 20 and 23 inclusive, or the free edges 30 thereof are brought together and passed or fed between two guide rollers 35 as is indicated in Figs. 5 and 8 of the drawing, after which said strips are passed between two steam boxes 36 and then through and 35 between two heat and feed rollers 37, and, in practice, the outer faces of the sheet 30 and strip 20 are brushed by brush devices 38 prior to the passage of said sheet and strip into and between the rollers 35 to raise 40 the nap of the material employed in said sheet and strip.

The method of operation of the apparatus diagrammatically illustrated in Figs. 5 and 8 and the construction of which is above set out, consists in passing the sheet 30 and the 45 separate strips 20 to 23 inclusive between the rollers 35 and steam boxes 36, and heat and feed rollers 37 in which operation said sheet and strips are steamed to prevent the shin- 50 ing of the sheet 30 and strip 20 after passing through the heat and feed rollers 37, and said heat and feed rollers serve to fuse the gutta percha strips 22 and 23 and cause the sheet 30 and strips 20 and 21 to closely adhere, and after the sheet 30 and strips 20 55 and 21 have been secured together and pass beyond the heat and feed rollers a predetermined portion or workpiece 39 is cut from the free edges of said parts by a suitable 60 knife 40.

After a predetermined number of the workpieces 39, one of which is illustrated in Figs. 5 and 8 of the drawing, have been produced in the manner above set out, a predetermined number of said workpieces are

placed one upon another on a suitable work-bench or support 41 as indicated in Fig. 9 of the drawing, in which figure twelve of said workpieces are shown and a suitable die 42 or cutter device is employed for stamping 70 out, or stamping from, the separate work-pieces 39 two of the parts 19, similar to that shown in Figs. 2 and 3 of the drawing, and the result of this stamping or cutting operation with the die 42 is illustrated in Fig. 7 75 of the drawing.

In addition to cutting the lapels 17 and collar portions 18 and cut-out portions 24 of the separate parts 19 of the garment, the sleeve openings 43 and shoulder portions 80 44 are also cut in this operation.

It will be noted on a consideration of Fig. 5 of the drawing that, in the above described operation of feeding the sheet 30 and strips 20 to 23 inclusive, into and between the rollers 35 and 37 and steam boxes 36 said strips are placed centrally of the sheet 30 in the manner illustrated in Fig. 5, and in this way, and by employing a suitable die 42, the separate parts 19 of the garment may be cut 90 from each of the workpieces 39 in a single operation, and this method of operation produces a very effective as well as economical means of producing the desired result, and forms lapels and collar portions on the separate parts 19 of the garment, the construction and dimensions of which would always be the same and also leave the attaching flaps 26 at the inner end portions of the lapels 17 and collar portions 18.

The last step in the method of forming the separate parts 19 of the garment consists in forming the stitching or pressed line 25 on the lapels and collar portions 17 and 18 of the garment, said line extending upwardly 105 from the cut-out portions 24 as clearly illustrated in Figs. 2 and 10 of the drawing, and this line, as above set out, may be formed or produced by stitching in the usual or any desired manner, or by a suitable die which 110 would form a pressed line, the appearance of which would imitate or resemble that of a stitched line.

In Figs. 11 and 11^a, I have shown a slight modification in the method of making the 115 separate parts 19 of the garment from the strip 30 fed into and through the apparatus as illustrated in Figs. 5 and 8 of the drawing, and in this form of construction two of each of the strips 20, 21, 22 and 23 are fed into 120 and through the apparatus at the opposite edge portions of the sheet 30 to form a workpiece blank 45, one of which is shown in Figs. 11 and 11^a, and the opposite side edge portions of which are provided with 125 the strips 20 to 23 inclusive, or the strips 20 and 21 attached to the sheet 30 by the gutta percha strip 22 and 23, and in such manner as to form the attaching flaps 26, as in the construction shown in Figs. 1 to 10 inclusive. 130

In stamping the separate parts 19 from the workpieces 45 shown in Figs. 11 and 11^a a die 42 of different construction is employed and the separate parts 19 of the garment are 5 cut out in the manner illustrated in Fig. 11^a, in which the lapel and collar portions 17 and 18 are at the outer edges of the separate parts of the garment instead of in the central portion thereof, as shown in Figs. 1 to 10 inclusive. This construction is shown merely to indicate another possible method of producing the same result shown in Figs. 1 to 10 inclusive but, in practice, I prefer to employ the method shown in said first 15 named figures.

In Fig. 12 of the drawing I have shown another modification of the construction shown in Figs. 1 to 10 inclusive, in which the knife 40 is omitted and a rotary roller 20 knife or cutter device 46 is employed, and is adapted to cut from the sheet 30 and the strips 20 and 21 secured thereto in the manner shown in Figs. 1 to 10 inclusive, the separate parts 19 of the garment alternately, 25 at the opposite sides of the sheet 30 in the manner illustrated at the right of Fig. 2 of the drawing, and the object of this construction is to facilitate the saving of the material employed by cutting the parts 19 from 30 the sheet 30 and strips 20, and 21, as illustrated in said figure.

It will be understood that while I have shown, or diagrammatically illustrated three methods of producing or forming the separate parts 19 of the garment, that my invention is not limited to these forms of apparatus nor to the exact steps in the process herein set out, nor to any particular size, dimensions or shape of the parts 19, and various changes in and modifications of the details herein shown and described may be made, within the scope of the appended claims, without departing from the spirit of my invention or sacrificing its advantages.

It will be understood that the separate parts 19 of the garment when completely formed are provided at the back with attaching devices whereby they may be connected in the usual manner in the manufacture of garments of the class specified, and it will be apparent that the left and right, or the separate parts of each garment are made from each of the work-pieces 39. The formation of the lapels and collar by my improved method or by the use of the gutta percha strips and cutting out said lapels and collar by dies or other cutting devices in the manner disclosed a more perfectly formed lapel and collar is produced, and especially the V-shaped or cut-out portions 24 thereof, and said lapels and collar are also provided with the desired stiffness or rigidity in the production thereof so that the same will keep their proper form and 65 always present a neat appearance.

With my improvement, or method of procedure, it is not necessary to fold, stitch or bind the edges of the lapels and collar in any way, said edges being formed and finished by the cutting process by which said 70 lapels and collars are formed, and this is also true of the V or V-opening 24 between the collar and the lapels and by means of my process these parts of the garment are given a more highly finished appearance 75 than if they were folded and stitched or bound in the usual way.

Having fully described my invention, what I claim as new and desire to secure by Letters Patent, is:—

1. The method of making a garment of the class described and providing the same with lapels and a collar, which consists in providing a body sheet of fabric material and facing material for the lapels and collar, said facing material being of much less transverse dimensions than said sheet, securing said facing material to said sheet with adhesive material, leaving parts of said facing material free to form attaching flaps, 90 and cutting and fashioning the parts thus secured together to form the lapels and collar from the said sheet and from the facing material secured thereto.

2. The method of making a garment of 95 the class described and providing the same with lapels and a collar, which consists in providing a sheet of fabric from which the body portion of the garment is made and a lapel and collar fabric facing strip, securing a predetermined portion of said facing strip to a predetermined portion of said sheet by adhesive material, and cutting and fashioning the parts of the garment from said sheet and strip in such manner as 100 to form a lapel and a part of a collar on each part of the garment from that portion of the fabric sheet to which the fabric strip is secured and to form attaching flaps from 105 that part of said strip not secured to the body sheet.

3. The method of making a garment of 110 the class described and providing the same with lapels and a collar, which consists in providing a sheet of fabric material of predetermined dimensions and from which the body portion of the garment is made also a plurality of strips of fabric material of less transverse dimensions than said sheet and securing said strips together and to said 115 sheet by adhesive material, cutting separate garment parts from said sheet and strips in such manner as to form a lapel and part of the collar on each part of said garment from that part of the sheet to 120 which said strips are secured, and marking each of said parts in such manner as to distinguish the lapel from the collar portion of said parts.

4. The method of making a garment of 130

the class described and providing the same with lapels and a collar, which consists in providing a sheet of fabric of predetermined dimensions and from which the body part 5 of the garment is made, also a strip of fabric of less dimensions than said sheet and which is secured to said sheet by a strip of adhesive material of less width than said strip whereby portions of said strip are left free 10 to form attaching flaps at the opposite sides of said strip, and cutting separate garment parts from said sheet and strip in such manner as to form a lapel and a part of a collar on each part of the garment from that part 15 of the sheet to which said strip is secured.

5. The method of making a garment of the class specified and providing the same with lapels and a collar, which consists in providing a fabric sheet of predetermined width 20 from which the body portion of the garment is made, securing a plurality of strips of fabric of predetermined width to the central portion of said sheet by strips of adhesive material of less width than said fabric strips, then cutting the separate parts 25 of the garment from the said sheet with said strips secured thereto in such manner as to form a lapel and a part of the collar on each part of the garment from that part 30 of the sheet to which said strips are secured, and marking the parts thus produced so as to distinguish the lapels from the collar.

6. The method of making a garment of 35 the class specified and providing the same with lapels and a collar, which consists in providing a fabric sheet of predetermined dimensions from which the body portion of the garment is formed, securing to said 40 sheet by means of adhesive material a strip of fabric of less width than the body sheet, the adhesive material being also of less width than said strip, feeding the sheet and strip into and through a suitable machine 45 to first brush the external faces of said fabric sheet and strip, then steaming said faces, then fusing the strip of adhesive material and compressing the fabric strip onto the sheet to secure the same together, and then 50 cutting the separate parts of the garment from the sheet and the strip of fabric secured thereto in such manner as to form a lapel and a part of the collar on each part of said garment from that part of the 55 sheet of fabric to which the strip of fabric is secured and to form attaching flaps on each of said parts inwardly of the lapel and collar portions thereof.

7. The method of making a garment of 60 the class described and providing the same with lapels and a collar, which consists in providing a sheet of fabric of predetermined width, a strip of similar fabric of less width than said sheet, an interlining strip of the

same width as the first named strip and 65 gutta percha strips of less width than said first named strips and located between the separate strips and said sheet, and feeding said sheet and strips into and through a suitable machine to first brush the external 70 faces of said sheet and said strip, then steaming said faces, then fusing said gutta percha strips and compressing the fabric and lining strips together and onto said sheet to secure the same together, and then 75 cutting the separate parts of the garment from the sheet of fabric and the strip secured thereto in such manner as to form a lapel and a part of a collar on each part 80 of said garment from that part of the sheet to which the fabric and lining strips are secured.

8. A burial garment of the class described comprising a fabric sheet from which the body portion of the garment is made, a facing material of less width than said sheet and secured thereto by adhesive material and the lapel and collar portions of the garment being composed of said sheet and the facing material secured thereto. 85

9. A burial garment of the class described composed of a sheet of material from which the body portion of the garment is made, and lapel and collar facing strips secured to predetermined parts of said sheet by adhesive material, the lapels and collar being composed of said sheet and the facing strips secured thereto and means for distinguishing the lapels from the collar. 90

10. A burial garment of the class described composed of separate body parts of fabric material, each of which is provided with lapel and collar edge portions, fabric facing strips partially secured to said edge portions by adhesive material so as to form 100 attaching strips inwardly of said edge portions, and said edge portions with the strips secured thereto being provided with a lapel and part of a collar on each of said body parts. 105

11. A burial garment of the class described composed of separate parts of fabric material having lapel and collar edge portions, fabric facing strips partially secured to said edge portions by adhesive material 110 so as to form attaching strips inwardly of said edge portions, said edge portions and the strips secured thereto being provided with a lapel and a part of a collar on each of said body parts and the facing strips being marked to distinguish the lapels from the collar. 115

12. A garment of the class described composed of separate parts, each of which is provided with a lapel and a part of a collar 120 formed from a sheet of fabric material from which the body portion of the garment is made, a strip of similar material and an

interlining strip, said strips being secured together and to said fabric by a sheet of adhesive material.

13. A garment of the class described composed of separate parts each of which is provided with a lapel and a part of a collar formed from a sheet of fabric material from which the body portion of the garment is made, a strip of similar facing material, 10 and an interlining strip, parts of said strips being secured together and to the sheet by

adhesive material and the unattached portions of said strips forming attaching flaps.

In testimony that I claim the foregoing as my invention I have signed my name in 15 presence of the subscribing witnesses this 18th day of March, 1919.

HARRY T. LOOMIS.
